Primary Examiner — Paula Allen Greene*(74) Attorney, Agent, or Firm* — Leydig, Voit & Mayer, Ltd.(57) **CLAIM**

The ornamental design for an earcup of headphones, as shown and described.

DESCRIPTION

FIG. 1 is a front perspective view of an earcup of headphones, showing my new design.

FIG. 2 is a rear perspective view thereof.

FIG. 3 is a left side view thereof.

FIG. 4 is a right side view thereof.

FIG. 5 is a front view thereof.

FIG. 6 is a rear view thereof.

FIG. 7 is a top view thereof; and,

FIG. 8 is a bottom view thereof.

The drawings of FIGS. 1-8 have portions that are stippled to represent contrast in color.

Where utilized, the broken lines show portions of the earcup that form no part of the claimed design.
